UNITED STATES PATENT OFFICE.

JAMES C. MEEM, OF BROOKLYN, NEW YORK, ASSIGNOR OF ONE-HALF TO FREDERICK L. CRANFORD, OF BROOKLYN, NEW YORK.

TUNNEL-SHIELD.

1,246,134.

Specification of Letters Patent.

Patented Nov. 13, 1917.

Application filed September 18, 1914. Serial No. 862,275.

To all whom it may concern:

Be it known that I, JAMES C. MEEM, a citizen of the United States, residing at Brooklyn, in the county of Kings and State 5 of New York, have invented certain new and useful Improvements in Tunnel-Shields, of which the following is a full, clear, and exact specification.

This invention relates to tunnel shields, 10 such as are used for subterraneous and subaqueous excavation, and more especially to those in dry subterraneous excavations where it may not be necessary to use compressed air, but where the spaces around the tunnel 15 left by the advance of the tail of the shield must be back filled as nearly as possible.

The invention has for its object to improve the construction of the shield itself, and at the same time to provide means 20 whereby the tunnel rings may be prevented from settling and distorting when the shield is advanced, and the space around the tunnel ring left by the tail of the shield may be more easily and completely filled against 25 the collapse of the surrounding material, causing settlement above. As at present constructed, tunnel shields consist of heavy 30 plates or segments forming a tube, made to fit the exterior rings of the tunnel as closely 35 as possible, but leaving sufficient space so that the shield can be moved forward when one tunnel section has been completed. It is desirable to cover the tunnel rings as far as practical with a permanent covering, and 40 also to fill the space between the outer perimeters of the shield and tunnel against collapse of material from without, and the distortion of the tube from within. Various methods have been employed, such as inflat- 45 able bags placed between the tunnel ring and the shield, fibrous materials and the like, to prevent the escape of compressed air and the consequent influx of water, but very little has been done to prevent the settle- 50 ment caused by the failure to fill the spaces left by the shield tail in advancing. With the solid forms of shields heretofore em- 55 ployed difficulty has been encountered in filling the space around the tunnel left by the shield when it is pushed forward. The present method most commonly employed is to enter a pipe from within and force liquid 60 concrete or grout through this pipe so as to surround and protect the tunnel tube. It is

impracticable, however to insert the grout in 55 this manner as the outer material frequently collapses before the grout can be placed or before it is sufficiently set to be of any value.

The present invention has for its object to provide an improved construction of shield 60 whereby a protective covering around the tunnel tube can be laid as each tunnel section is erected, and also permitting the shield to be pushed forward without disturbing this covering and leaving an absolute minimum of voids behind the shield. 65 At the same time this covering performs the function of a filling between the interior of the shield and the exterior of the tunnel tube, reducing to a minimum any settlement or collapse of the tube itself. These 70 objects are attained by the shield herein described, which comprises generally a tubular section having the usual forward cutting edge, and the rear tubular portion somewhat 75 larger in diameter than the exterior of the tunnel. Bridging this space, so as to both support the tail of the shield on the tunnel tube and to guide it, are longitudinal ribs carried by the shield itself. The spaces 80 thus formed between the tunnel tube and the interior of the shield tail, and between the ribs, can be filled immediately after the tube segments are erected, so that the only 85 spaces left by advancing the shield are those due to the thickness of the ribs and to the small thickness of the shield tail itself, which can be reduced to a minimum thickness by virtue of the bridging strength of 90 the ribs supporting it. By grouting, even 95 the spaces left by the ribs may be filled, these being so small in comparison with the spaces left by a thick tail, that the grout may fill them before the surrounding material can collapse. Thereby the tunnel tube 100 may be almost completely covered as the shield is advanced. Any desired filling material may be used in these spaces, such as gravel, soft concrete or specially molded segmental covering blocks, or both. The 105 spaces thus left will be so small that settling will be reduced to a minimum, and water can easily be kept out, or air, if used, easily prevented from escaping. There will be no tendency of the tunnel sections to distort owing to a large and unfilled space left by the shield tail at the sides and bottom between the outer edge of the tail and the tube.

In the accompanying drawings is illustrated one embodiment of the invention, wherein,

Figure 1 is a cross section of a tunnel shield embodying the invention taken on the line 1—1 of Fig. 2; and

Fig. 2 is a longitudinal section taken on the line 2—2 of Fig. 1.

The shield 1 is considered to be advancing to the left in the direction of the arrow, Fig. 2, by power applied thereto such as by hydraulic jacks 2 or other suitable means. The forward or cutting end of the shield may be of any well known construction, and the shield may have a bulk-head according to common practice, or not, as desired. This invention is however, especially concerned with the rear end of the shield, which instead of being of heavy plate metal practically fitting the outside of the tunnel rings 3, is of thinner metal somewhat spaced therefrom, and provided with spaced interior longitudinally extending ribs 4 which bear, or almost so, on the exterior of the tunnel tube segments. See Fig. 1. Thereby, between the rear of the shield 1 and the exterior of the tunnel segments 3 and the successive ribs 4, are formed segmental spaces 5. These segmental spaces 5 are to be filled with a filling as 6, immediately after the tube segments are erected, and before the shield is advanced. See Fig. 2. The filling and covering material 6 may be gravel, or concrete poured therein from within the shield, or specially formed segmental blocks, or bricks. The ribs 4 constitute supports for the relatively light tubular tail 1, and are normally slightly spaced from the tunnel rings 3, so that the shield may be directed up or down, or laterally as desired. Also, the ribs will bear on the tunnel rings sufficiently to prevent collapsing of the shield tail by outside pressure, without interfering with the advancing of the shield. The forward end will of course be internally strengthened as shown so as to be self sustaining. The shield tail will carry the ribs 4 with it, without disturbing the filling 6, and the relatively thin spaces due to the thickness of the ribs and the thickness of the shield tail will be substantially filled by the surrounding material without endangering adjacent buildings, even if the liquid grout above re-

ferred to is not employed. At the same time, the filling 6 prevents inrush of water, or escape of air. Consequently, the advancing of the shield does not necessitate the moving of an inflatable filling to the new position, nor does it leave large voids which have to be filled with grout after the shield is moved in order to prevent the completed tunnel sections from sinking, as is the case with an ordinary thick or heavy tail shield. By this invention, shield excavations can be more quickly made owing to avoidance of delays in back filling by previously used methods, and settling of the completed tunnel, and of surrounding material and buildings is prevented.

Having thus described my invention, I declare that what I claim as new and desire to secure by Letters Patent, is:

1. In combination, a tunnel wall, a shield spaced around the front end portion of said wall and projecting beyond the same, means acting between said wall and shield for advancing the shield, internal guides on the shield in the space between said wall and shield, said guides being spaced apart circumferentially so as to leave spaces between them accessible under the shield in front of the wall, and filling material in said spaces.

2. In combination, a tunnel shield having a forward cutting end, longitudinal interior ribs on its rear end portion, a completed front end tunnel wall portion within said shield, said ribs constituting guiding supports for the shield on said completed wall portion, and filling material in the spaces between said ribs.

3. In combination with a tubular tunnel, a tubular tunnel shield sliding exteriorly thereon comprising a tube larger than the exterior diameter of the tunnel, internal longitudinal ribs on the shield tube adapted to guide and support the shield on the tunnel tube, and filling material in the spaces between said ribs and within said shield.

In testimony whereof I affix my signature, in presence of two witnesses.

JAMES C. MEEM.
